STOCKING

Charles C. Kraus, Humboldt, Tenn., assignor to Wayne Knitting Mills, Humboldt, Tenn., a corporation of Indiana

Filed July 20, 1961, Ser. No. 65,995

Term of patent 14 years

(Cl. D47—7)

FIG. 1 is a front elevational view of a lady's stocking embodying my new design. The rear thereof is conventional.

FIG. 2 is an enlarged fragmentary view of the upper portion thereof.

I claim:

The ornamental design for a stocking, as shown and described.
